UNITED STATES PATENT OFFICE.

GIUSEPPE MARCONI, OF GENOA, ITALY.

PHOTO-PRINTING PRESS.

Application filed February 21, 1925, Serial No. 10,808, and in Italy December 20, 1924.

This invention relates to improvements in photo-printing presses for use in printing photographs either by the action of sun light or by artificial light, the object of the invention being to provide an improved device of this character which is simple in construction and which can be operated precisely and rapidly.

With the above and other objects in view, the invention consists in the construction, combination and arrangement of devices hereinafter described and claimed.

In the accompanying drawings

Figure 1 is a plan, partly in section, of a photo-printing press constructed in accordance with my invention.

Figure 2 is a transverse section of the same on the line $x-x$ of Figure 1.

Figure 3 is a longitudinal section of the same on the line $y-y$ of Figure 1.

Figure 4 is a detail section.

Figure 5 is a detail perspective of the means for securing the movable part of the cover to the frame of the press.

The press as shown in the annexed drawings, is composed of a rectangular wooden frame 1 of the usual type, but having the sides higher and narrower than those of the usual press frames. The frame is provided on its inner side with the usual flange to support the glass plate 3 against which the photo paper and eventually the negative film is pressed by the plate cover. Said cover is formed by two pieces 2 and 2' which are hinged together. Each of the two pieces of the cover is pressed by a metallic or other elastic cross bar 4, fastened thereto. The ends of these cross bars are arranged to enter corresponding slots 4^a cut in the frame and are kept in this position by spring hooks 5 which are encased in the sides of the frame and fixed thereto by means of integral corner points as shown, or by other similar means. Within the longer sides of the said frame, and precisely in the portions between the slots in which the ends of the cross bars enter and the corners of the frame, are longitudinal slots 6^a open towards the interior and closed by the outer edges of the frame.

In the said slots 6^a are levers 6, the fulcrums of which are formed by wood screws 7, and each having an outwardly turned arm arranged to engage one of the spring hooks.

The opposite ends of said levers bear against the inner ends of cylindric buttons 8, which

are placed in corresponding holes in the frame and project from the outer edge of the frame.

The movable portion of the plate cover has on the side which is opposite to the hinge, a stop 9 shaped as shown in Figures 1, 2, 3 and 5, and formed by a piece of V-shaped metallic plate and provided at the outer end with oppositely extending finger pieces 10. The said stop has its union end embedded in the cover 2, while the projecting portion is arranged to tightly fit in a slot 9^a in the frame 1, the width of the said slot being slightly less than that of the section of the V-shaped piece 9 which consequently needs a little pressure to enter into the said slot and remains fixed therein, the said V-portion of the stop 9 being of such length that, when the cover is placed in the frame, and the said stop is in the slot 9^a, the finger pieces 10 projecting out of the frame sufficiently for engagement by a finger.

The operation is as follows:

After having placed in the frame the plate with the negative and the photo-paper, the plate cover is closed and is held in closed position by the stop 9. The cross pieces 4 are pressed inwardly by the fingers until their ends are engaged and held by the spring hooks 5. Hence, owing to the elasticity of the cross pieces, they press the cover firmly against the photo-paper. During the printing, whenever a control of the proceeding of the impression be desired, it will be sufficient to push down the buttons 8 of the portion of the cover to be raised. These buttons act on the levers 6 which push outwardly on the spring hooks, thus setting free the corresponding cross piece 4 which by elasticity springs out of the hooks. Then by disengaging the stop 9 from the slot 9^a by means of the finger pieces 10, the portion 2 of the cover can be raised, thus allowing the intermediate controls of the printing of the paper.

When the desired point of impression of the paper has been reached, by pushing all of the four buttons 8, both the cross pieces will be disengaged from the hooks, and after setting free the plate cover by acting on the stop 9, the impressed paper can be taken out.

While I have herein shown and described a preferred form of my invention, I would have it understood that changes may be made in the form, proportion and construction of

the several parts without departing from the spirit of my invention and within the scope of the appended claim.

Having now described and ascertained the nature of my said invention and in what manner the same is to be performed, I declare that what I claim is:

A photo-printing press, comprising a frame, a glass pane therein, a cover for arrangement in the frame and on the said pane and comprising a pair of hingedly connect-

ed members, one of said members being provided with a cross sectional V-shaped elastic stop, projecting from the free side thereof, said frame being provided in one side with 15 a slot to receive said stop and so arranged that the sides of said slot may be frictionally engaged by said stop, and detachable means to press said cover against said pane.

In testimony whereof I affix my signature.

GIUSEPPE MARCONI.
